[57] CLAIM

The ornamental design for a combined ceiling fan motor
housing, support rod, pull cords and light fixtures unit, as
shown and described.

DESCRIPTION

FIG. 1 is a front elevational view of a combined ceiling fan
motor housing, support rod, pull cords and light fixtures unit
showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a perspective view thereof.

The support rod has been shown broken away in FIGS. 1, 2,
3, and 6 and 7 to indicate indeterminate length.
